CHEST ON CHEST

Norman N. Hekler, High Point, N.C., assignor to Worth Furniture, a division of Gravely Furniture Co., Inc., Martinsville, Va., a corporation of Virginia

Original design application Nov. 27, 1962, Ser. No. 72,612. Divided and this application Mar. 26, 1963, Ser. No. 74,132

Term of patent 3½ years

(Cl. D33—6)

FIG. I.

Des. 198,793

PAGE 2

FIG. 4.

FIG. 2.

Des. 198,793

PAGE 3

FIG. 3.

FIG. 1 is a perspective view of a chest on chest, showing my new design;

FIG. 2 is a front elevational view thereof;

FIG. 3 is a side elevational view thereof; and

FIG. 4 is a top plan view of the same.

The back of the article is plain and unornamented.

This application is a division of my application Serial No. D. 72,612, filed November 27, 1962, now abandoned.

I claim:

The ornamental design for a chest on chest, as shown and described.
